UNITED STATES PATENT OFFICE.

FREDERICK CARTER AND MARCUS MCCHESNEY, OF NORTH PLATTE,
NEBRASKA.

ALARM FOR MILL-ELEVATORS.

SPECIFICATION forming part of Letters Patent No. 430,921, dated June 24, 1890.

Application filed February 27, 1890. Serial No. 342,006. (No model.)

To all whom it may concern:

Be it known that we, FREDERICK CARTER and MARCUS MCCHESNEY, citizens of the United States of America, residing at North 5 Platte, in the county of Lincoln and State of Nebraska, have invented certain new and useful Improvements in Mill-Elevators, being an alarm to indicate choking in elevator-shafts and to prevent the same, of which the following is a specification, reference being had therein to the accompanying drawings.

This invention pertains to certain new and useful improvements in grist-alarms, having for its object the provision of a noiseless alarm 15 continuously operated by the endless conveyer-belt when the latter is free from obstruction.

The invention consists of a "bob" or short rod pivotally secured in a conveyer-casing, so 20 that one end is acted upon by the buckets on the conveyer-belt, its projecting end being thereby moved up and down, substantially as hereinafter fully set forth, and particularly pointed out in the claims.

25 In the accompanying drawings, Figure 1 is a view in perspective of an elevator-casing, showing our invention and having parts broken away. Fig. 2 is an enlarged detail sectional view.

30 Referring to the drawings, A designates a conveyer-casing, a an endless conveyer-belt, and a' the buckets secured thereto.

B is a bob or short rod pivotally supported near one end by a transverse pin b, which is 35 passed through eyes b' of a plate b², secured to a sectional board b³, removably secured within and forming a portion of the elevator-casing. Coincident apertures are formed in plate b² and board b³, through which is projected the bob or rod B, so as to be free to move therein.

In practice the bob or rod is continuously 40 operated by the endless belt of buckets, which latter strike against the inner inclosed end thereof in their upward movement, causing the raising and lowering of the outer end of

such bob, its inner end being lowered as soon as freed from contact with the bucket, it being the heavier of the two arms of the bob. When the conveyer becomes choked, causing 50 the buckets to cease movement, the same will be indicated by the failure of the bob to move. In this manner it is readily ascertained that the grist has caused a stoppage, and the same can be at once remedied. It will also be observed that this alarm is entirely noiseless— 55 i. e., it serves its purpose by continuous up and down movement, which ceases when there is anything wrong—and hence the device is extremely simple, cheap, and durable, and not 60 liable to get out of order or become deranged.

We claim as our invention—

1. In combination with an elevator-casing and an endless belt of buckets, a bob or rod projected through said casing and normally 65 occupying an inclined position, its inner end being on the line of travel of said buckets, whereby a vibratory movement is imparted to said bob or rod by the passage of the buckets, substantially as set forth. 70

2. The combination, with an elevator-casing having an aperture and an endless belt of buckets, of a bob or rod, pivotally secured in said aperture and having its inner end in proximity to said buckets, substantially as set 75 forth.

3. The combination, with an elevator-casing and an endless belt of buckets, of a sectional board secured in said casing and having an aperture, a plate secured to said board 80 having opposite eyes, a bob or rod, and a pivotal pin projected through said eyes for pivotally securing said bob or rod, substantially as set forth.

In testimony whereof we affix our signatures 85 in presence of two witnesses.

FREDERICK CARTER.
MARCUS MCCHESNEY.
